UNITED STATES PATENT OFFICE

2,167,916

PRODUCTION OF YARN CONTAINING STAPLE FIBER FROM CONTINUOUS FILAMENTS

William Ivan Taylor and Alfred Herbert Woodruff, Spondon, near Derby, England, assignors to Celanese Corporation of America, a corporation of Delaware

Application February 5, 1937, Serial No. 124,208
In Great Britain February 22, 1936

6 Claims. (Cl. 19—1)

This invention relates to the production of yarns containing staple fibers from continuous filaments.

A bundle of continuous filaments may be converted directly into yarn containing staple fibers by causing said bundle to pass into contact with a cutting surface positively driven in the same direction as the bundle but at a different speed, and pressing the bundle against the surface so that the surface exerts a cutting action on the filaments in the bundle. The cutting surface may conveniently be in the form of an abrasive roller, or with advantage a fluted roller such as is described in United States application S. No. 15 23,804, filed May 28, 1935, and the bundle of continuous filaments may be pressed against the cutting surface by means of another roller, or as is described in United States application S. No. 726,264, filed May 18, 1934, by means of a stationary pressing surface. It is an object of the present invention to provide an improved method and apparatus for converting a bundle of continuous filaments directly into a yarn containing staple fibers.

According to the present invention means are provided to draw a bundle of continuous filaments between and in contact with a cutting surface and a further surface by which the bundle is pressed against said cutting surface, and the contact of the bundle of continuous filaments with said surfaces is utilised to bring about the desired movement of said cutting surface.

The cutting action of the cutting roller depends upon the difference of speed between the surface of the roller and the continuous filament bundle, and in order to give this difference in speed the mere inertia and the friction in the bearings of the cutting roller and/or the pressing roller, if such is employed, may be relied on.

The conversion of continuous filaments in the bundle into staple fibers by the device described above does not substantially affect the degree of twist which the bundle may possess. However, when the bundle has little or no twist, the product should be collected, after the conversion of the filaments into staple fibers, by a twisting and winding operation to impart to it a twist, which may be the amount of twist required in the final product, or may need to be augmented by further twisting. In either case, the twist so imparted during winding maintains the coherence of the product. Alternatively, the coherence may be maintained by reason of a substantial initial degree of twist in the continuous

filament bundle, which twist, as previously stated, is practically unaffected by the conversion.

By way of example two forms of apparatus according to the invention will now be described in greater detail with reference to the accompanying drawing, in which:

Fig. 1 is a front elevation of a cutting roller unit according to the invention;

Fig. 2 is a side elevation from the left of the unit shown in Fig. 1 together with means for drawing the yarn through the unit and a twisting spindle for collecting the yarn; and

Fig. 3 is a side elevation from the right of a modified form of the unit shown in Fig. 1.

In Figs. 1 and 2 the unit comprises a frame 1 with a stub axle 2 on which a cutting roller 3 is mounted in ball bearings indicated at 4. The surface of the roller 3 is grooved with sharp-edged flutes 5 cut at an angle of 45° to the axis of the roller, so as to give the desired cutting action. The frame also carries two plain slotted steel bearings 6 to receive the spindle 7 of pressing roller 8 provided with flutes 9, which are parallel to its axis so that the flutes 9 cross the flutes 5 in the roller 3. The slotted bearings 6 permit the roller 8 to be lifted or dropped vertically immediately above the cutting roller 3 and for this purpose a lever 10 is provided pivoted about a point 11 and held by means of a spring 12 secured to a point 13 on the frame 1 against one or other of two stops 14, 15. When, as is shown in Figs. 1 and 2, the lever 10 is held against the stop 14 the weight of the roller 8 rests upon the roller 3. When it is desired to lift the roller 8, the lever 10 is pushed down against the stop 15 and the roller 8 is lifted by the engagement of the spindle 7 with a notch 16 in the end of the lever 10.

The cutting roller 3 is provided on one side with a braking surface 17 against which bears a brake spring 18 secured at 19 to the frame 1. The brake spring 18 is pressed against the surface 17 by means of a screw 20 having a knurled head 21 and screwing into a lug 22 on the frame 1. A guide 23 is provided on the frame 1 for leading the yarn into the nip between the rollers 3, 8 and a further guide 24 is provided to conduct the yarn that has passed through the nip vertically downwards away from the roller 3.

In the operation of the device the yarn 25 consisting of continuous filaments is led by the guide 23 to the nip of the rollers and is drawn through the rollers and through the guides 23 and 24 by means of three rollers 26, 27, 28. The roller 28 is a driven roller and drives the roller 27

which in turn drives the roller 26, by friction. The rollers 26 and 27 are mounted in a bracket 29 provided with slotted bearings 30. The slotted bearing 30 accommodating the roller 27 opens in front of the bracket 29 whereby the roller 27 can be dropped in in such a way that the yarn 25 is caused to pass behind the roller 27 and in front of the rollers 26 and 28.

The yarn 25 passing between the rollers 3, 8 drives those rollers by the contact it makes therewith, but at a peripheral speed lower than the speed at which the yarn is drawn. This is ensured by adjustment of the brake spring 18 by means of the screw 20. The roller is retarded by the non-positive resistance to rotation imposed by these means, so that the requisite difference in speed between the surface of the roller 3 and the yarn 25 is obtained. By reason of the cutting nature of the surface of the roller 3, and of this difference of speed, the filaments in the yarn 25 are cut at intervals along the length of the yarn so that the yarn issues from the nip as a staple fiber product 31 which is engaged by the rollers 26, 27, 28 and fed to the balloon guide 32 of a cap spinning device 33 by means of which the yarn is twisted, and wound on to a package 34.

In order to vary the force with which the yarn 25 is pressed against the cutting roller 3 the weight of the pressing roller 8 may be varied. For this purpose cavities indicated at 35 are provided in the body of the roller 8 which cavities will be empty when a bundle 25 of fine denier is employed. For heavier deniers, however, greater pressure is needed, and weights indicated at 36 are inserted in the cavities 35. By these means the weight of the roller 8 and consequently the force with which the yarn 25 is pressed against the cutting roller 3 may be varied.

In Fig. 3 is shown a modification of the device shown in Fig. 1, and at the top of Fig. 2. This figure shows the opposite side of the device to that shown in Fig. 2 in order that the additional elements may be clearly seen. These additional elements comprise a series of vanes 37 secured to the cutting roller 3 and an air nozzle 38 controlled by a cock 39 by means of which nozzle a current of air may be directed against the vanes 37, so as to assist the yarn 25 in rotating the cutting roller 3. It will be understood that these additional means do not entirely relieve the yarn 25 of the work of rotating the roller 3, nor are they so powerful as to cause the roller 3 to rotate with a peripheral speed equal to the speed of the yarn 25. These additional means are of particular convenience with yarns of fine denier which would be too weak to drive, without assistance, a pair of rollers of sufficiently robust construction to withstand wear and handling. Moreover, it enables yarns of any desired weight to be dealt with by the same unit.

The device described above may be applied to several other types of textile apparatus that are provided with or comprise means for drawing the yarn through the device. Thus it may be necessary to provide a set of gripping rollers similar to the rollers 26, 27, 28 through which the yarn passes after leaving the rollers 3, 8 in order to draw the yarn positively past the cutting surface 3.

Types of textile apparatus other than the twisting device 33 to which the device of the present invention may be applied are doubling means, to which two or more of the staple fiber yarns 31 proceeding from the device may be fed, pirn winding machines, either of the type

adapted to twist the yarn as it is wound on the pirn or of the type adapted to wind without twisting, and coning machines which wind the yarn into the form of a large package without twisting. Again the staple fiber yarn 31 produced according to the present invention may be fed directly to a warping machine in which case (as well as in the case of the doubling machine) the rollers 3, 8 may be made wide enough to take a number of bundles 25 of continuous filaments passing through it in parallel. In the same way the yarns 31 produced according to the invention may be fed to a drumming or sectional warping device. Or again, the device according to the present invention may be applied directly to such machines as circular knitting machines, the yarn 31 being passed through the device according to the present invention at the speed at which it is fed to needles.

The invention may be applied to continuous filament bundles of many different kinds. Thus, the continuous filaments in the bundle may consist of cellulose acetate or other cellulose derivatives or they may consist of reconstituted cellulose, e. g., viscose, cuprammonium and nitrocellulose filaments or they may be natural silk filaments. Moreover, two or more bundles of similar or dissimilar continuous filaments may be associated together, e. g., by doubling, and passed together through the device according to the invention to produce a single yarn containing staple fibers. Moreover, the yarns produced according to the invention may be associated with other yarns, e. g., by doubling, after they have been converted from a bundle of continuous filaments into yarn containing staple fibers, and such association may be effected continuously with such conversion or at a subsequent stage.

Having described our invention, what we desire to secure by Letters Patent is:

1. Method of producing yarn containing staple fiber from continuous filaments, said method comprising drawing a bundle of continuous filaments between and in contact with a cutting surface and a further surface, pressing said bundle against said cutting surface by means of said further surface, utilising the pull of said filaments to drive said cutting surface in the same direction as, but at a lower speed than, the bundle of filaments, and non-positively driving said cutting surface in order to assist the driving action of the filaments whereby said filaments are cut individually at intervals along the length of said bundle of filaments.

2. Method of producing yarn containing staple fiber from continuous filaments, said method comprising drawing a bundle of continuous filaments between and in contact with a cutting surface and a further surface, pressing said bundle against said cutting surface by means of said further surface, utilising the pull of said filaments to drive said cutting surface in the same direction as the bundle of filaments, and imposing a continuous non-positive resistance against the motion of said cutting surface so that it is driven at a lower speed than said bundle of filaments.

3. A device for the production of yarn containing staple fiber from continuous filaments, said device comprising a member having a cutting surface, a further member adapted to press against said cutting surface a bundle of filaments drawn between said members, neither of said members being positively driven, said cutting surface being movable by the pull of said

filaments so as to move in the same direction as, but at a lower speed than, said filaments whereby said filaments are individually severed at intervals, and non-positive driving means for assisting said filaments to move said cutting surface.

5. Apparatus for the production of yarn containing staple fiber from continuous filaments, comprising a roller having a cutting surface, a pressing roller adapted to press against said surface a bundle of filaments drawn between the said rollers, said rollers being freely mounted so that said cutting surface is driven in the same direction as said bundle of filaments by the pull in said bundle of filaments, but at a lower speed 10 whereby said filaments are individually severed at intervals, and external means for assisting said filaments to drive said cutting roller.

15. Apparatus for the production of yarn containing staple fiber from continuous filaments, comprising a roller having a cutting surface, a pressing roller adapted to press against said surface a bundle of filaments drawn between the said rollers, said rollers being freely mounted so

that said cutting surface is driven in the same direction as said bundle of filaments by the pull in said bundle of filaments, but at a lower speed whereby said filaments are individually severed at intervals, vanes carried by said roller and a nozzle adapted to direct a current of air against said vanes so as to assist the filaments in driving said cutting roller.

5. Apparatus for the production of yarn containing staple fiber from continuous filaments, comprising a roller having a cutting surface, a pressing roller adapted to press against said surface a bundle of filaments drawn between the said rollers, said rollers being freely mounted so that said cutting surface is driven in the same direction as said bundle of filaments by the pull in said bundle of filaments, but at a lower speed 10 whereby said filaments are individually severed at intervals, and adjustable braking means for retarding the motion of said cutting roller.

CERTIFICATE OF CORRECTION.

Patent No. 2,167,916.

August 1, 1939.

WILLIAM IVAN TAYLOR, ET AL.

It is hereby certified that error appears in the printed specification of the above numbered patent requiring correction as follows: Page 2, second column, lines 52, 53 and 54, claim 1, strike out the words "whereby said filaments are cut individually at intervals along the length of said bundle of filaments" and insert the same before "and" in line 50, same claim; line 63, claim 2, after "filaments" insert whereby said filaments are cut individually at intervals along the length of said bundle of filaments; and that the said Letters Patent should be read with this correction therein that the same may conform to the record of the case in the Patent Office.

Signed and sealed this 19th day of September, A. D. 1939.

Henry Van Arsdale,

Acting Commissioner of Patents.
